MORTARING DEVICE

Augustus L. Ezell, Bessemer, Ala.

Application April 2, 1937, Serial No. 134,550

3 Claims. (Cl. 72—128)

This invention relates to a mortar device and more particularly to the class of devices for use in constructing or building brick walls or other types of masonry. The main object of the invention is to provide a process device of this character in which mortar may be rapidly and conveniently applied to the building of a wall in an even and workmanlike manner with considerable speed and avoidance of the waste of mortar. A further object of the invention is to provide a process device of this character which is very simple in construction, thoroughly reliable and efficient in operation and inexpensive to manufacture.

15 The right is reserved to manufacture the device out of any material that may best be suited for the purpose, and it is also understood that minor changes, variations and modifications may be made providing the same come properly within the scope of the claims and do not depart from the spirit of the invention. Also it is understood that the device may be made in any size depending on the class of masonry for which it is to be used.

25 In the accompanying drawing Fig. 1 is a plan view of the device; Fig. 2 is an end view of Fig. 1 including cross member indicated by *y*—*y*; Fig. 3 is a side elevation of the device resting on a wall; Fig. 4 is an enlargement showing means for holding the guide flange in place; Fig. 5 is an enlargement of means for holding the main boards in place; Fig. 6 is an enlargement of means showing how a flange is held in place and boards in proper position on slide rods; Fig. 7 is a sectional view showing tapered edges of main boards and means for holding same in proper position; Fig. 8 is an enlargement showing the means for adjusting the edge gauge.

Similar reference numerals refer to similar parts throughout the several views.

Referring to the drawing 1, 2 and 3 indicate the main members of the device consisting of slats or boards. These slats are slideable on rods 4 having set screws 5 to hold them in any desired position. Part of a brick wall is indicated by 6 and the device is held in proper alignment by

flange 7 which is held in place by screws 8 fitting into slots 9 having washers 10 acting as clamps. When the device is in use 11 indicates mortar in position. The center board or slat 2 may be provided with recesses as indicated by 11—*a*. Flange 7 is adjustable and may be moved towards the wall to an extreme position as indicated by 12.

Having described my invention I claim:

1. A device of the class described comprising a number of boards mounted on rods passing through said boards, said boards being slideable on said rods and having set screws to hold said boards in the desired position with relation to each other, said boards being provided with beveled edges where the same come in contact with the mortar, suitable L shaped guides attached to two of said boards and disposed to rest along the edge of the wall when the device is in use, said L shaped guides being adjustable by means of slots and clamping screws. 15

2. A mortaring device of the class described comprising three boards mounted parallel on metal rods passing through said boards, said boards being slideable on said rods and having set screws to hold said boards in the desired parallel position with relation to each other, said boards being provided with beveled edges where the same come in contact with the mortar, suitable L shaped guides attached to two of said boards and disposed to face against the edge of the wall 25 when the device is in use, said L shaped guides being adjustable by means of slots and clamping screws. 30

3. A mortaring device of the class described comprising three members mounted on rods passing through said members, said members being slideable on said rods and having set screws to hold said members in the desired position with relation to each other, said members being provided with beveled edges where the same come in 35 contact with the mortar, suitable L shaped guides attached to two of said members and disposed to rest along the edge of the wall when the device is in use, said L shaped guides being adjustable by means of slots and clamping screws. 40
